UNITED STATES PATENT OFFICE.

JAMES W. ALEXANDER, OF OLD CHURCH, VIRGINIA.

MOWER-KNIFE SHARPENER.

1,274,659.

Specification of Letters Patent.

Patented Aug. 6, 1918.

Application filed November 17, 1917. Serial No. 202,559.

To all whom it may concern:

Be it known that I, JAMES W. ALEXANDER, a citizen of the United States, residing at Old Church, in the county of Hanover and State of Virginia, have invented certain new and useful Improvements in Mower-Knife Sharpeners; and I do hereby declare the following to be a full, clear, and exact description of the invention, such will enable others skilled in the art to which it appertains to make and use the same.

This invention relates to sharpeners for mower knives and the primary object of the invention is to provide a pivoted sharpening element carried by the guard finger having spring means to normally hold the same in frictional contact with the cutter blade, so that the cutter blade will be sharpened as the same moves back and forth in the guard.

Another object of the invention is the provision of means for allowing the sharpening element to be lifted out of engagement with the cutter blade and at right angle thereto, so that the sharpening element can be readily repaired when necessary.

A further object of the invention is the provision of a pin, which is adapted to be inserted in the rear end of the guard for engaging the under surface of the sharpening element for holding the same out of engagement with the cutter knife when so desired.

A still further object of the invention is to provide a device of the character described, which is durable and efficient in use, one that is simple and easy to construct and one that can be placed upon the market at a reasonable price.

With these and other objects in view, the invention consists in the novel construction, arrangement and formation of parts, as will be hereinafter more specifically described, claimed and illustrated in the accompanying drawings, forming a part thereof, in which:

Figure 1 is a plan view of the invention applied to a cutter blade,

Fig. 2 is a central horizontal section through the cutter guard,

Fig. 3 is a vertical section through the cutter guard showing the sharpening element in operative position in full lines and showing the same in its inoperative positions in dotted lines.

Fig. 4 is a detail perspective view of the stationary cutter blade,

Fig. 5 is a transverse section taken on the line 5—5 of Fig. 3, and

Fig. 6 is a detail transverse section taken through the upper portion of the guard showing the means for holding the sharpening element out of engagement with the cutter blade.

Referring to the drawing in detail, wherein similar reference numerals designate corresponding parts throughout the several views, the numeral 1 designates the cutter blade which may be of any desired construction or configuration and is adapted to be reciprocated by the slide plate 2 mounted

in the guard 3 for the blade. A stationary blade 4 is removably secured to each guard 3 by means of a detachable fastening element 5. The stationary blade 4 is gradually tapered toward its outer end to conform to the shape of the guard and has its longitudinal edges serrated to provide a cutting surface to coöperate with the cutting blade 1. The rear end of the stationary cutter blade 6 is enlarged as at 7 and the edges of the same are beveled inwardly as at 8 and the same are received in a cut out portion 9 in the guard 3. An elongated opening 10 is formed in the central portion of the stationary blade 4 and this opening registers with a similar formed recess 11 formed in the guard 3, for a purpose which will be hereinafter more fully appear. The guard 3 is provided with a rearwardly extending attaching lug 12 by

which the same may be secured to a mowing machine. The outer end of the guard 3 is tapered as at 13 in the ordinary manner and pivoted at its end is the sharpening element 14. The sharpening element 14 comprises

the reduced shank 15 and the blade 16, and the same is formed of a suitable sharpening steel. A pivot pin 17 extends transversely through the outer end of the guard 3 and pivotally supports the sharpening element 14. The upper end of the guard 3 is bifurcated as at 18 and the sharpening element 14 is adapted to extend through the slot. A leaf

spring 19 is provided for normally holding the sharpening element 14 in a lowered position and in engagement with the reciprocating cutter blades 1. The leaf spring 19 has an enlarged outer end 20 and is pivotally positioned in place by means of a pivot pin

21 which extends through the enlarged portion and the outer end of the guard 3. The leaf spring 19 normally holds the blade of

110

the cutter sharpening element in engagement with the cutter blade and the blade 16 thereof extends through the opening 10 in the stationary cutter blade 4 and in the recess 5 11 formed in the guard. A pin 22 is provided for holding the sharpening element out of engagement with the cutter blade 1 and against the tension of the leaf spring 19. This pin is adapted to be inserted in a transversely 10 extending aperture 23 formed in the inner upper end of the guard 3. The pin 22 is provided at its central portion with a notch 24 which is adapted to receive the sharpening element and hold the same out of engagement with the cutter blades. 15

When it is desired to repair the sharpening element 14 the spring 19 is swung on its pivot pin 21 and out of engagement with the sharpening element and then the same can be swung on its pivot at a right angle to the guard. When the sharpening element 14 assumes this position any repairs necessary can be readily made on the same. 20

From the foregoing description it can be seen that an improved mower sharpener is provided, which is normally held in engagement with the cutter blade by means of a leaf spring, but is capable of being held out of engagement with the same by means of a 25 pin or swung on its pivot pin to assume a position, whereby repairs can be readily made on the same.

In practice, I have found that the form of

my invention, illustrated in the accompanying drawings and referred to in the above 35 description, as the preferred embodiments, is the most efficient and practical; yet realizing the conditions concurrent with the adoption of my device will necessarily vary, I desire to emphasize the fact that various minor 40 changes in details of construction, proportion and arrangement of parts may be resorted to, when required, without sacrificing any of the advantages of my invention as set forth. 45

What I claim as new is:

A mower knife sharpener comprising a knife guard, a sharpening element pivotally secured to the guard adjacent the outer end thereof, a leaf spring engaging the upper 50 edge of said sharpening element for normally holding the same in engagement with the cutter blade, said leaf spring being pivotally secured to the outer end of said guard and adapted to be swung out of engagement with 55 the sharpening element whereby the same can be swung upward and out of engagement with the rear end of said guard, when so desired.

In testimony whereof I affix my signature 60 in presence of two witnesses.

JAMES W. ALEXANDER.
